United States Patent

Des. 235,604
Patented July 1, 1975

235,604

SAUCEPAN OR THE LIKE

Alice Kiernan, Lewiston, Maine, and Patricia A. Luzier and Gregory Mirow, Corning, N.Y., assignors to Corning Glass Works

Filed Apr. 20, 1973, Ser. No. 353,121

Term of patent 14 years

Int. Cl. D7—02

U.S. Cl. D7—97

Fig. 1

Fig. 2

Fig. 3

Fig. 4

FIG. 1 is a side elevational view of a saucepan or the like embodying our new design, with the opposite side being identical.

FIG. 2 is an end elevational view, the opposite end being identical.

FIG. 3 is an enlarged fragmental view in elevation.

FIG. 4 is an enlarged fragmental view in elevation. The characteristic feature of the design resides in the particular ornamentation applied to the outer wall, as shown.

We claim:

The ornamental design for a saucepan or the like, as shown and described.
